DOOR CHECK AND CLOSER.

1,203,413.

Specification of Letters Patent. Patented Oct. 31, 1916.

Application filed August 16, 1916. Serial No. 115,120.

To all whom it may concern:

Be it known that I, ALBERT J. ROSENTRETER, a citizen of the United States, and a resident of Boonton, in the county of Morris and State of New Jersey, have invented certain new and useful Improvements in Door Checks and Closers, of which the following is a specification.

The invention pertains to door checks and closers adapted for sliding doors of the character ordinarily employed at the different floors of buildings for guarding the entrances to the elevator shaft or shafts and permitting, when open, access to the elevator car or cars when arrested at the several floors of the building. These sliding doors are of various types, there being in some instances a stationary door or panel imitating a door with one sliding door to be moved by the operator on the elevator car, and in other instances such panel with two sliding doors arranged to telescope one along the other, and in other instances the said panel representing a door is in fact a door and hinged so that it may be opened and fully expose the car, this latter class usually being employed in connection with elevator cars designed to carry freight and in which use it is desirable that a wide opening be provided for the admission of desks and the like to the car.

..The features of my invention will be applied to the sliding door, or to the outer sliding door when two of such doors are used, and to a stationary abutment, which may be afforded by the door framing, and said features comprise means enabling the attendant on the car to slide the door or doors to open position, and means for automatically closing the door or doors and checking the same on their closing movement so that the door or doors will positively close but without undue noise.

One of the purposes of my invention is to provide door checking and closing mechanism which may be applied to sliding doors already installed and to new doors without regard, in general instances, to the construction of the building or that portion thereof adjacent to the elevator shaft. In accordance with my invention the entire checking and closing mechanism may be applied to the exposed portions of the door or doors and jamb without difficulty and without modification in their construction or

arrangement or in the construction or arrangement of the parts of the building adjacent to the elevator shaft.

I present the preferred construction embodying my invention in this application as applied to two doors, one being a sliding door and the other an imitation door, which is sometimes hinged so as to be occasionally used as a door, said mechanism being shown as attached at one end to the sliding door and at the other end to the jamb of what may be said to be a stationary door.

My invention comprises a pair of toggle levers in the form of bars of substantially equal length pivoted together at their adjoining ends and at their outer ends pivotally connected, respectively, with the sliding door and door-jamb of the imitation door or panel, together with checking means connected with one of said toggle levers and spring mechanism of special character, for effecting the closing of the doors subject to the action of the checking mechanism, the closing-spring being placed under tension during the opening of the sliding door.

The invention will be fully understood from the detailed description hereinafter presented, reference being had to the accompanying drawings, in which:

Figure 1 is an elevation of a sliding door and an imitation or panel door for an elevator shaft equipped with door opening, closing and checking means embodying my invention, this figure showing the side of the doors facing the elevator shaft; Fig. 2 is a view on a larger scale and partly broken away and partly in section of the door operating mechanism illustrated in Fig. 1 on a reduced scale; Fig. 3 is a vertical transverse section through a portion of the same, taken on the dotted line 3—3 of Figs. 1 and 2; Fig. 4 is a vertical transverse section through a portion of the same, taken on the dotted line 4—4 of Fig. 2; Fig. 5 is a vertical longitudinal section, partly broken away, through a portion of the closing spring mechanism, taken on the dotted line 5—5 of Fig. 3; Fig. 6 is a detached elevation of the adjoining portions of the toggle levers and spring mechanism, the levers being shown as folded upwardly, as happens during the opening of the door; Fig. 7 is a detached view, partly broken away, of those portions of the mechanism directly connect-

100

105

110

ed with the sliding door, Fig. 7 being presented to indicate the manner of detaching the toggle levers from the sliding door, and Fig. 8 is a top view, partly broken away, and on a larger scale of those portions of the mechanism directly connected with the sliding door.

In the drawings, 10 designates a sliding door of usual type, and 11 a stationary or 10 imitation door or panel behind which, in the usual course of practice, the elevator operator stands, with his right hand near the starting and stopping devices of the elevator car.

15 12, 13 indicate toggle levers pivotally connected together near their adjoining ends by means of a rivet or pin 14, the outer end of the lever 12 being pivotally secured by means of a pin 15 with a plate 16 rigidly fastened 20 to the door 10, while the outer end of the lever 13, which is composed of two parallel bars or members 17, as shown in Figs. 3 and 4, is pivotally secured by a pin 18 between ears 19 formed on the upper end of a bracket 25 plate 20 which is rigidly fastened to the door-jamb 21.

The lever 12 is a single member or bar and at its inner end is interposed between the inner ends of the parallel bars or members 30 17 constituting the toggle lever 13, and the pin 14 extends through said lever 12 and both members of the lever 13. Adjacent to its inner end the lever 12 is formed in its upper edge with a recess 22 which, 35 when the levers are in their extended position, shown in Figs. 1 and 2, receives a transverse pin 23 carried by the lever members 17. At its outer end the lever 12 contains an aperture 24 which freely passes upon the pin 15, which extends outwardly from the bracket plate 16, the outer end of the lever 12 being at the outer side of the upper end 40 of a handle lever 26 which is also hung upon the pin 15. The handle lever 26 when in its operative position, shown in Figs. 1 and 2, inclines downwardly and outwardly, and said lever is provided at its lower end with a suitable grip or auxiliary handle member 45 27 of any suitable character, while at its upper end the lever 26 has secured to it a plate 28 affording an arm 29 to engage the lower edge of the toggle lever 12 and a finger 30 to lap upon said lever 12 adjacent to the pin 15 for maintaining said lever in position on 50 said pin during the usual operation of the door, as shown in Fig. 2. The upper outer end of the lever 12 is cut away, as at 31 (Fig. 7), so that when the handle lever 26 is turned upwardly, the outer end of the 55 lever 12 may be slipped from off the pin 15, which is the condition represented in Fig. 7, the lever 12 being there shown as having been slipped off from the pin 15 and in that way become detached from the door 10. 60 Fig. 7 also indicates the readiness with which

the lever 12 may be applied to the pin 15 and in that way to the door 10. I deem it highly desirable that the lever may be detached from the pin 15 and applied thereto without requiring anything further than to 70 turn the handle lever 26 upwardly so that the finger 30 connected therewith may not interfere with the application of the lever 12 to position on the pin 15 or its removal therefrom. When the handle lever 26 is 75 in its hanging operative position, shown in Figs. 1 and 2, the end of the arm 29 connected therewith engages the lower edge of the lever 12 inwardly of the pin 15, and hence when said lever 26 is pulled toward 80 the right, looking at Fig. 2, it will cause the toggle lever 12 to turn upwardly on the pin 15, as indicated in part, by dotted lines in Fig. 2, and thereupon the inner end of the lever 12 acting against the pin 23 will start 85 the lever 13 upwardly and finally the opening movement of the door will cause said levers to fold upwardly, as indicated in part, in Fig. 6. Apart from its design, the novelty in the handle-lever 26 resides in the provision of means whereby when said lever is 90 in its operative position, it maintains the outer end of the lever 12 upon its securing means and that when said handle lever is turned to an inoperative position, it releases the lever 12 to be detached from said securing means.

Upon the members 17 constituting the toggle lever 13 is mounted a cylinder 32 formed from a piece of sheet metal whose 100 side edges are flanged downwardly, as at 33, and secured between said members 17, as represented in Figs. 2, 3 and 5. The cylinder 32 is elongated and contains a coiled door-closing spring 34, one end of which has a bearing against the end 35 of the cylinder 32 and the other end of which has a bearing against a follower 36 mounted upon a rod 37 which extends through a portion of the spring 34 and is, within said spring, connected at its left hand end (looking at Fig. 2), with a chain 38, which maintains the follower 36 against the end of the spring and said spring under tension. The rod 37 at its left hand end has a pivotal connection 115 with the chain 38 and at its right hand end is threaded and engages a threaded hole 39 in the left hand end of a hollow cylindrical nut and guide 40. The left hand end of the combined nut and guide 40 is always within 120 the cylinder 32, as shown in Fig. 2, and during the opening of the door and the folding upwardly of the toggle levers 12, 13 said nut and guide 40 is pulled within the cylinder 32 and serves through the follower 36 125 as means for moving against and compressing the spring 34. The nut 40 is elongated so that it may have a free sliding movement within the cylinder 32 and serve as a guide for the left hand end of the spring and parts 130

connected therewith, and the nut 40 is preferably formed at its outer end with apertures 41 to receive any suitable tool by which the nut 40 may be turned upon the rod 37, the 5 nut being adjustable on said rod and adapted by its adjustment to regulate the tension of the spring 34 and the force said spring shall exert during the closing action of the door. The chain 38 is hooked upon an arm 10 42 extending upwardly from a pair of disks 43 which are secured upon opposite faces of the inner end of the lever 12. The pin or rivet 14 hereinbefore referred to extends through the disks 43. The disks 43 represent 15 plates suitable for carrying the arm 42 and they also space the adjacent faces of the toggle lever members 17 from the sides of the lever 12, this being desirable since during the opening of the door the arm 42 pulls the 20 chain 38 toward the left and between said members 17, as shown in Fig. 6. During the opening of the door and the folding upwardly of the toggle levers 12, 13, the arm 42, by pulling on the chain 38, draws the 25 nut 40 and follower 36 inwardly along the cylinder 32 with the result that the spring 34 is compressed; and thereupon when the door is released to close, said spring 34, by its expansive force, causes the chain 38 to 30 pull on the arm 42 and turn the levers 12, 13 downwardly to the extent permitted by their securing pins and the pin 23.

As suitable means for checking the closing action of the door under the force of the 35 spring 34, I provide a checking cylinder 44 which is pivoted to the bracket plate 20 and has the upper end of its piston-rod 45 pivotally connected with the toggle lever 13 by means of a screw or pin 46 which is located 40 below the pin 18 and disposed inwardly therefrom, so that upon the folding upwardly of the toggle lever 13, said lever may operate as a crank for pulling the piston-rod 45 upwardly within the cylinder 44. 45 Upon the piston-rod 45 is provided a valved piston 47 whose valve will open freely during the ascent of the piston-rod and substantially or wholly close the port through the piston during the descent of the piston-rod, 50 thereby trapping the air or liquid that may be at the time within the lower part of the cylinder and compelling the travel of the same around the piston and through a restricted by-pass 48 whose passage may be 55 regulated by a screw-valve 49 in a customary way. I do not limit my invention to the details of construction of the checking cylinder 44, since such details may be variously modified in the present condition of the art. 60 When the door is opened and the toggle levers 12, 13 caused to fold upwardly, the lever 13 will draw upwardly on the piston-rod 45, and thereafter when the door is released to close, the toggle lever 13 will force 65 the piston-rod 45 downwardly and the liquid

or air below the piston will serve to check the action of the spring 34 and compel the door to move gently when reaching its closing point.

The plate 28 on the handle-lever 26 has 70 a laterally extending member 50 which when said lever is swung toward the right, as in opening the door, will engage the edge of the plate 16, as a stop, to limit the movement of said lever, this engagement taking place 75 after the toggle levers have started to fold upwardly, and thereafter the said lever is employed as a substantially rigid bar to slide the door to its open position.

A pin or rivet 51 extending transversely 80 through the lever members 17 and flanges 33 may be used to secure the cylinder 32 on said members.

The operation of the various parts of the mechanism constituting my invention has 85 been given hereinbefore in connection with the explanation of the construction of said parts, and therefore it is believed that further description as to the operation of the mechanism is not necessary. 90

What I claim as my invention and desire to secure by Letters Patent, is:

1. Sliding door operating mechanism comprising, in combination, toggle levers pivotally connected together and one of which is 95 pivotally connected with the sliding door and the other to an abutment, spring mechanism connected with said levers for closing the door, and means for checking the closing of the door, said spring mechanism comprising an elongated cylinder mounted on one of 100 said levers, a coiled spring therein, and flexible means connected with the other lever and engaging one end of said spring for compressing the spring on the folding of the levers during the opening of the door. 105

2. Sliding door operating mechanism comprising, in combination, toggle levers pivotally connected together and one of which is pivotally connected to the sliding door 110 and the other to an abutment and one of which levers is formed of two spaced apart bars, and spring mechanism connected with said levers for closing the door, said spring mechanism comprising an elongated cylinder mounted on said bars and having flanges extending downwardly thereon, a coiled spring within said cylinder, means for regulating the tension of said spring, and means connected with the other lever and one end 115 of said spring for compressing said spring on the folding of the levers during the opening of the door. 120

3. Sliding door operating mechanism comprising, in combination, toggle levers pivotally connected together and one of which is pivotally connected to the sliding door and the other to an abutment, and spring mechanism connected with said levers for closing the door, said spring mechanism comprising 125 130 135 140 145 150 155 160 165 170 175 180

an elongated cylinder mounted lengthwise on one of said levers, a coiled spring therein having a fixed bearing at one end, a follower engaging the other end of said spring and 5 flexible means connected with the other lever and said follower for compressing said spring on the folding of said levers during the opening of the door.

4. Sliding door operating mechanism comprising, in combination, toggle levers pivotally connected together and one of which is pivotally connected to the sliding door and the other to an abutment, and spring mechanism connected with said levers for closing 10 the door, said spring mechanism comprising an elongated cylinder mounted on one of said levers, a coiled spring therein having a fixed bearing at one end, a follower engaging the other end of said spring, an 15 arm projecting from the other lever and a chain connected with said arm and said follower for compressing said spring on the folding of said levers during the opening of the door.

5. Sliding door operating mechanism comprising, in combination, toggle levers pivotally connected together and one of which is pivotally connected with the sliding door and the other to an abutment, and spring 20 mechanism connected with said levers for closing the door, said spring mechanism comprising an elongated cylinder mounted lengthwise on one of said levers, a coiled spring therein having a fixed bearing at one 25 end, a follower engaging the other end of said spring, an arm on the other lever, flexible means connected with said arm and said follower for compressing said spring on the folding of said levers during the opening of the door, and means for regulating the tension of said spring.

6. Sliding door operating mechanism comprising, in combination, toggle levers pivotally connected together and one of which is 45 pivotally connected with the sliding door and the other to an abutment, and spring mechanism connected with said levers for closing the door, said spring mechanism comprising an elongated cylinder mounted 50 on one of said levers, a coiled spring therein having a fixed bearing at one end, a follower engaging the other end of said spring, an adjustable nut engaging said follower for regulating the tension of said spring, an arm 55 projecting from the other lever and a chain engaging said arm and thence extending through said spring and having on its end a threaded rod in engagement with said nut, whereby said arm becomes connected with 60 said follower for compressing said spring on the folding of said levers during the opening of the door.

7. Sliding door operating mechanism comprising, in combination, toggle levers pivotally connected together and one of which is 65

pivotally connected with the sliding door and the other to an abutment, and spring mechanism connected with said levers for closing the door, said spring mechanism comprising an elongated cylinder mounted 70 on one of said levers, a coiled spring therein having a fixed bearing at one end, a follower engaging the other end of said spring, an adjustable nut engaging said follower for regulating the tension of said spring, an 75 arm projecting from the other lever and a chain engaging said arm and thence extending through said spring and having on its end a threaded rod in engagement with said nut, whereby said arm becomes connected with said follower for compressing said spring on the folding of said levers during the opening of the door, and said nut being elongated and cylindrical and with reasonable snugness fitting the bore of 80 said cylinder.

8. Sliding door operating mechanism comprising, in combination, toggle levers pivotally connected together and one of which is pivotally connected to the sliding door and 90 the other to an abutment, and one of which levers is formed of two spaced apart bars receiving between them at their inner ends the inner end of the other lever, plates secured to the opposite faces of said other 95 lever, an arm projecting from said plates, and spring mechanism connected with said levers for closing the door, said spring mechanism comprising an elongated cylinder mounted lengthwise on said bars, a 100 coiled spring within said cylinder having a fixed bearing at one end, a follower engaging the other end of said spring and flexible means connected with said arm and said follower for compressing said spring on the 105 folding of said levers during the opening of the door.

9. Sliding door operating mechanism comprising, in combination, toggle levers pivotally connected together and one of which is 110 pivotally connected to the sliding door and the other to an abutment, and one of which levers is formed of two spaced apart bars receiving between them at their inner ends the inner end of the other lever, plates secured to the opposite faces of said other 115 lever, an arm projecting from said plates, and spring mechanism connected with said levers for closing the door, said spring mechanism comprising an elongated cylinder 120 mounted lengthwise on said bars, a coiled spring within said cylinder having a fixed bearing at one end, a follower engaging the other end of said spring and flexible means connected with said arm and said fol- 125 lower for compressing said spring on the folding of said levers during the opening of the door, and said plates being disks and said flexible means being a chain adapted to be drawn between the inner ends of said 130

bars when the toggle levers are folded upwardly.

10. Sliding door operating mechanism comprising, in combination, toggle levers 5 pivotally connected together and one of which is pivotally connected to an abutment, a plate fastened to the sliding door having a stud or pin on which the outer end of the other lever is pivotally mounted, a handle lever pivotally swung upon said stud or pin and having a part to engage said other lever inwardly of said stud or pin for starting said levers toward their folded position and also a part overlapping the end of said other 10 lever to retain it upon said stud or pin when the handle lever is in operative position and adapted to permit the release of said other lever from said stud or pin when it, said handle lever, is turned to an inoperative 15 position, and means for closing the door.
11. Sliding door operating mechanism comprising, in combination, toggle levers pivotally connected together and one of

which is pivotally connected to an abutment, a plate fastened to the sliding door having 25 a stud or pin on which the outer end of the other lever is pivotally mounted, a handle lever pivotally swung upon said stud or pin and having a part to engage said other lever inwardly of said stud or pin for starting 30 said levers toward their folded position and also a part overlapping the end of said other lever to retain it upon said stud or pin when the handle lever is in operative position, and means for closing the door, the outer end of said other lever being cut away at one edge so as to become free of 35 said overlapping part when the handle lever is turned to an inoperative position.

Signed at New York city, in the county 40 of New York and State of New York, this 15th day of August A. D. 1916.

ALBERT J. ROSENTRETER.
